[57] **CLAIM**

The ornamental design for a folding table, as shown and described.

DESCRIPTION

FIG. 1 is a side elevational view of a folding table showing my design;

FIG. 2 is an end elevational view;

FIG. 3 is a top plan view; and

FIG. 4 is a side elevational view thereof in folded condition.

The side and end of the table not shown are mirror images of the side and end shown in FIGS. 1 and 2, respectively.

FIG. 1

FIG. 2

FIG. 4

FIG. 3
